UNITED STATES PATENT OFFICE.

VICTOR S. PEARLMAN, OF CHICAGO, ILLINOIS, ASSIGNOR TO VICTOR S. PEARLMAN & CO., OF CHICAGO, ILLINOIS, A CORPORATION OF ILLINOIS.

LAMP-SHADE FRAME.

1,244,639.

Specification of Letters Patent. Patented Oct. 30, 1917.

Application filed December 11, 1916. Serial No. 136,205.

To all whom it may concern:

Be it known that I, VICTOR S. PEARLMAN, a citizen of the United States, and a resident of Chicago, in the county of Cook 5 and State of Illinois, have invented certain new and useful Improvements in Lamp-Shade Frames, of which the following is a specification.

My invention relates to lamp shade frames 10 particularly to skeleton frames for supporting ornamental fabric or other material.

Lamp shades, particularly those for ornamental uses, are usually constructed by forming a skeleton supporting frame of wire 15 and securing thereon the ornamental fabric or other material. The frame usually has an upper marginal ring of wire with spokes radiating inwardly and secured to an inner supporting ring usually of wire, this inner 20 ring being of a diameter to enter a shade holder to be received by the holder screws. This is a very impractical and inefficient arrangement for it is a tedious, disagreeable and laborious task to get the ring properly 25 into the holder and in such engagement with the supporting screws that the shade will be rigid and secure and will hang straight. The object of my invention is to improve on such prior construction and to 30 provide a frame which can be more readily and accurately secured in the ordinary forms of holders. This I accomplish by providing an inner supporting ring of special sheet metal construction, the ring flaring 35 upwardly and being provided with holes or slots in its sides for receiving the inner ends of the frame spokes to which the ring is then secured as by bending of the spoke ends and soldering.

40 In the accompanying drawings I have shown a frame embodying my invention. In these drawings—

Figure 1 is a perspective view of a frame, 45 Fig. 2 is a diametral vertical sectional view, and

Fig. 3 is a diametral sectional view of a modified arrangement.

The frame shown comprises upper and lower marginal rings 5 and 6 of wire, these 50 rings being connected by vertical ribs 7, the upper ends of which are deflected radially with reference to the upper ring to form spokes 8 which terminate equidistant from the frame ring center. A sheet metal

supporting inner ring 9 is provided which 55 has the lower cylindrical section 10 and the upper flaring section 11. In the lower cylindrical section transverse slots 12 are provided for receiving the inner ends of the spokes 8. The supporting ring is applied 60 to the spokes with the slots receiving the spoke ends, the wire spokes preferably fitting snugly in the slots to hold the supporting ring centrally with reference to the frame while the ring and spokes are secured 65 together as by soldering. Preferably longitudinal slots 13 are extended a distance from the upper ends of the slots 12, the supporting ring, after the spoke ends are received in the vertical slots, being given a slight 70 turn to bring the spoke ends into the longitudinal slots, such arrangement more securely holding the supporting ring in place preparatory to soldering.

As an additional means for centralizing 75 and holding the supporting ring the spoke ends may be bent at right angles as indicated at 14, Fig. 3.

With a supporting ring as described, the shade frame can be readily applied to and 80 accurately and rigidly secured in the ordinary forms of holder. In Fig. 2 a holder H of the ordinary type is shown, the holder comprising the cylindrical wall 15 and the top 16 on which the neck 17 extends upwardly for receiving a support, such as an electric light socket. The wall 15 has the ordinary screws 18 threading radially therethrough. To apply my improved frame 85 the screws 18 are withdrawn a sufficient distance to permit entrance of the supporting ring 9 and when the screws are then turned inwardly they engage against the outer sides of the curved flared section 11 and draw the ring upwardly to bring the spokes against 90 the lower edge of the holder H and the shade frame is then rigidly secured and accurately held. In shallower holders the upper edge of the supporting ring will be forced by the screws against the top 16 of 100 the holder to cause the frame to hang properly. After the frame has been thus accurately secured in the holder an electric light bulb can be readily inserted through the frame and supporting ring to be screwed 105 into the socket on which the holder is mounted. It is understood, of course, that ornamental fabric or other material is se-

cured to the skeleton frame to complete the shade. The marginal rings 5 and 6 can be circular, as shown, or elliptical, polygonal, or of other contour, depending upon the form of shade desired.

I do not, of course, desire to be limited to the exact construction and arrangement shown as modifications are no doubt possible which would still come within the scope 10 of the invention.

I claim as follows:

1. In a lamp shade frame, the combination of a skeleton structure for supporting shade fabric, spokes extending inwardly 15 from the top thereof, and a sheet metal supporting ring having slots adjacent its lower edge for receiving the inner ends of the spokes, the upper section of said supporting

ring being flared for coöperating with shade holder supporting screws.

2. In a lamp shade frame, the combination of a skeleton wire supporting structure 20 for shade fabric, wire spokes at the upper end of said structure, a sheet metal supporting ring having slots extending from its lower edge for receiving the inner ends of the wire spokes whereby said ring may be centered relative to the structure preparatory to soldering of the ring to the spokes, the upper part of said ring flaring to co-operate with shade holder screws.

In witness whereof I hereunto subscribe my name this 8th day of December, A. D., 1916.

VICTOR S. PEARLMAN.
